UNITED STATES PATENT OFFICE.

HAROLD ROWNTREE, OF KENILWORTH, ILLINOIS.

PASSENGER-CAR-DOOR MECHANISM.

1,073,930.

Specification of Letters Patent. Patented Sept. 23, 1913.

Application filed September 30, 1910. Serial No. 584,624.

To all whom it may concern:

Be it known that I, HAROLD ROWNTREE, a citizen of the United States, residing at Kenilworth, county of Cook, State of Illinois, have made a certain new and useful invention in Passenger-Car-Door Mechanism, of which the following is a specification.

This invention relates to passenger car door mechanism.

The object of the invention is to provide a car door mechanism for street and other passenger cars, which is simple and efficient, and wherein the operation of the doors may be easily accomplished and controlled.

A further object of the invention is to provide the sides of the car platform with doors so as to inclose the platform, and to control, mechanically or otherwise, the operation of the doors, to open or closed position, from a convenient point inside the platform or car body space, and from such a point as will afford a wide opening and passage through the platform side door way 25 and across the platform, to or from the body space of the car, to facilitate the entrance or exit of passengers without delay and without undue congestion, and in such relation as to enable the conductor to stand at the 30 point of door control out of the way of passengers to effect the door movements, to collect the fares, and to generally superintend the boarding and alighting of the passengers and the starting and stopping signals.

A further object is to provide means whereby the car platform may be provided with a wide side entrance when the doors are fully opened but which may be operated to control a part only of the doorway 35 closer to let off passengers, or another portion only to enable passengers to board the car, without effecting the entire opening of the platform side doorway.

A further object is to provide a double 45 set of doors for controlling the side doorway of the car platform, which are operable independently of each other.

A further object is to provide means of the character referred to having such arrangement and relation as to enable the ready application thereof to be made in the conversion of old style cars for fare-prepayment and pay-within operation and control.

Other objects of the invention will appear more fully hereinafter.

The invention consists substantially in the construction, combination, location and relative arrangement of parts, all as will be more fully hereinafter set forth, as shown 60 in the accompanying drawings, and finally pointed out in the appended claims.

In the drawings,—Figure 1 is a plan view of a car body and its platforms, showing a door mechanism embodying the principles 65 of my invention applied thereto. Fig. 2 is a broken view in vertical section showing a form of door operating mechanism embodying the principles of my invention. Fig. 3 is a similar view showing a modified arrangement of door operating mechanism in accordance with the principles of my invention. Fig. 4 is a view in horizontal section, looking downwardly, taken at a point above the gear 29 in Fig. 2.

The same part is designated by the same reference sign wherever it occurs throughout the several views.

In the modern practice of street or other passenger car constructions the tendency is 80 to provide means to insure the collection of fares, to insure the safety of passengers in boarding and alighting, and to facilitate the loading and unloading of the cars, particularly at points where the traffic is congested. The idea of fare prepayment as the passengers enter the car, or at a certain point inside the car, has been embodied in various proposed arrangements, and various means for insuring against boarding and alighting 85 accidents have been designed. The arrangement which has met with the greatest favor consists in providing the car platform with inclosing doors for the side entries or doorways thereof, and means located inside 90 the platform or car body space to control the operation of the door. These door operating means have been located at various points. For instance, in one arrangement, the operating means for the rear platform 100 side doors have been located at the front end of the car under control of the motorman. This is exceedingly objectionable for the reason that the control and operating of the doors at the rear end of the car, 105 is thereby imposed on the motorman in addition to his regular duties and whose attention should be devoted to the running of

the car and perhaps, the operation of the front doors, to let off passengers, in order to avoid the danger and peril of collision or other accident incident to the car operation. Moreover, this arrangement necessitates the location of the control of the rear platform side doors at a point where the operator thereof cannot personally supervise the boarding and alighting of passengers, but must depend on signals from the rear platform, thereby increasing the danger of boarding and alighting accidents at the rear end of the car, and causing delay in the running of the car. Another arrangement heretofore employed provides for the use of a double set of doors for the side openings of the platform, one set controlling what may be termed the entrance, and the other set the exit ways to and from the platform space on the same side, and means for operating both sets simultaneously. This involves an unnecessary amount of work in requiring the operation of both sets of doors on the same side of the platform, or the opening up and closing of both the entrance and the exit way whenever there is any door operation even though passengers are only boarding the car and none are alighting, or are alighting from the car and none are boarding at the same time. In other arrangements provision is made in the form of a railing, guard, post or other means, for separating the platform space into separate entrance and exit passages. This necessarily limits the available platform space and frequently requires the enlargement of this space in applying the arrangement to cars. Such enlargement of the platform space is not always possible, particularly where old style cars are to be converted into the present type, and, moreover, at congested points of travel, such arrangement causes delay in passengers boarding the car by reason of having to pass through a restricted passageway across the platform.

It is among the special purposes of my present invention to avoid these and other objections incident to the use of the arrangements above noted, and others now employed and to provide means which will afford a wide unobstructed passageway across the platform into the car body space, while at the same time inclosing the platform space by side doors controllable from a point within the platform, or car body space, and in convenient position to enable the doors to be operated to opened or closed position by the conductor who can thereby personally superintend the boarding and alighting of passengers at the rear end of the car, and consequently avoiding danger of boarding and alighting accidents, while at the same time enabling the conductor to collect the fares from passengers as they enter, or from the point of door control, either on the platform or

within the car body space, but so located as not to form an obstruction to a wide opening or passageway across the platform to and from the car body space, thereby greatly facilitating the handling of the passengers, particularly at terminals or other congested points of traffic. And I also propose to provide a double set of doors or door panels, for the platform side doorway, one set arranged on each of said doorways, the doors or panels arranged to be independently operated so that if a passenger is to board the car at any point or street crossing while none are to alight from the car at that point, or if a passenger is to alight and none are to board the car at the same stop, only the particular door or set required for boarding, or alighting, as the case may be, need be operated.

In the drawings I have shown, as illustrative of the principles of my invention, a form and arrangement which is simple and efficient for carrying out and accomplishing the objects and purposes above noted.

Reference letter A designates the car body space, and B, the platform space. I have shown the car as provided with a platform at both ends, though in this respect and in many other details hereinafter mentioned, my invention as defined in the claims, is not to be limited or restricted. The platforms are shown as provided with doorways on each side thereof, with a double set of doors or panels 5, 6 for the doorway on one side of the platform, and 7, 8, for the doorway on the opposite side of the platform. The particular construction, type, and inter-connection of the doors or panels, and the manner of their mounting and operation, may be varied throughout a wide range without departure from the spirit and scope of my invention as defined in the claims, and in the details thereof, form no part of the present invention. In the particular form shown to illustrate a practical and operative embodiment of my invention, the various doors or panels constituting a set 5, 6, 7 or 8, are hinged together at their meeting or proximate edges, the outer or primary member of each set being connected to a rock shaft, 9, 10, 11, 12, and the other members being guided in any suitable way to rock or swing into folded relation upon the primary member, as the latter is rocked or swung in opening the door. When in open position the panels or doors of each set are disposed transversely of the platform and car while in closed position said door or panel sections are distended into line with each other and in the direction of the length of the car.

The door panel sections 5, 6, are arranged to coöperate in controlling the doorway on one side of the platform, while the sections 7, 8, control the doorway on the opposite side of the same platform. The sets 5 and 13

7, may be regarded as controlling the exit ways for passengers alighting from the car, while the sets 6 and 8, may be regarded as controlling the entry ways for passengers 5 boarding the car, and by providing means for independently operating each set of panels, either one or the other of the entrance or exit ways may be opened or closed as occasion may require, without opening or 10 closing the other.

Any suitable means may be employed for effecting the opening and closing movements of the panel sections. A simple arrangement is shown for illustrative purposes, 15 wherein the shafts 9, 10, 11, 12, to which the primary section or panels of the various sets are respectively connected are respectively provided with crank arms 13, 14, 15, 16, and to each crank arm is connected one 20 end of an operating rod 17, 18, 19, 20, through which said crank arms, and with them their associated shafts and primary door panel sections are rocked.

I have shown the sets 5, 6, of door panels 25 arranged on one side of the platform, at one end of the car, and on the opposite side of the platform at the other end of the car. The sets 7, 8, are in similar relation. This is the arrangement for double-ended 30 cars where either end, according to requirements, may be utilized as the motorman's end. It is obvious, however, that my invention, as defined in the claims, is not to be limited in this respect. In this arrangement 35 the motorman is stationed on the platform at one end of the car and the conductor is stationed at the other end of the car. At the motorman's end of the car the doors on one side of the platform may be kept 40 closed all the time while those on the other side may be opened and closed to permit passengers to alight from the car. The passengers enter the car only at the rear or conductor's end, although they 45 may also alight from the car at that end, the doors on one side of the platform being kept closed while those on the other side are operated to open or close as occasion may require to permit entrance 50 or exit of passengers. With this arrangement the conductor and motorman may, if desired, shift their respective stations from one end of the car to the other according to the direction of travel of the car.

55 The door section actuating rods 17, 18, 19, 20, may be operated by any suitable or convenient operating mechanism. For illustrative purposes I have shown in Figs. 1 and 2, one arrangement for operating the rods 20, 21, 22, wherein said rods are connected to crank arms 21, 22, on gear wheels 40, 41, respectively meshing with racks 23, 24. These racks are connected to vertical rods 25, 26, which carry racks 27, 28, at their 60 other ends. Gear wheels 29, 30, respectively

engage said racks 27, 28, said gear wheels 29, 30, having crank arms 31, 32, by which they may be independently operated. This affords a very simple and efficient structure for the required purpose, though it is evident that other arrangements may be employed, and in Fig. 3, I have shown a modified arrangement wherein rod 19 is connected eccentrically to a disk or collar 33, carried at one end of a tube or pipe 34, the other end of said tube or pipe having an operating arm or lever 35, whereby said pipe may be rotated. The other door actuating rod 20 is similarly connected eccentrically to a disk or collar 36, on one end of rod or pipe 37, which extends through the pipe 34, and at its other end carries an operating handle 38. This arrangement has the advantages of simplicity and cheapness of construction. The operating rods 17, 18, for the door sections 7, 8, on the other side of the platform from the door sections 5, 6, may be actuated in a similar, or in any other suitable or convenient manner, and whether 70 independently or in unison. As these door sections are ordinarily designed to control the doorway only for the exit of passengers in alighting from the car, the necessity for independent operation of the sections 7, 8 does not ordinarily exist. In this case 75 80 85 90 95 100 105 110 115 120 125 130

The control devices for the respective sets of doors on opposite sides of the platform may be located at any suitable or convenient point. I have shown the door control lever 39 for the actuating rods 17, 18 of door panels 7, 8, as located on the front dash board of the car in convenient position to be operated by the motorman, and I have shown the control levers or handles 31, 32, or 35 38, located in convenient position to define a conductor's station from which station fares may be collected as passengers enter the car, and the sets 5, 6, of door panels may be independently operated as exigency may require. In the attainment of the full object and purpose of my invention, and in order to avoid obstructing the passage way between the car body and platform, and to secure the widest possible space, while still retaining the features of separate entrance and exit doors for the platform doorway, and a fare prepayment station, I locate the control devices for the door panels 5, 6, so as to define a conductor's station inside the platform or car body space and at one side of the passageway between the car body and platform spaces.

This station may be inside the transverse bulkhead partition between the car body space and platform, as shown at the left hand end of Fig. 1, or it may be outside of 5 said bulkhead partition as shown at the right hand end of Fig. 1.

Of course, it will be obvious that transverse bulkhead partitions and doors may or 10 may not be employed but since the platform sidedoors form a vestibuled platform, the bulkhead doors, ordinarily, are not required:

In practice I prefer to locate the conductor's station on that side of the passageway leading across the platform to the car 15 body space, which is farthest removed from the platform side doorway, that is, opposite said doorway, and I also prefer to use that portion of the platform side doorway which is nearest the end of the car as the entry 20 way for passengers boarding the car. With this arrangement of entry way and conductor's station the prepayment of fares by boarding passengers as they pass the conductor who is located on the far side of 25 said passageway, insures the collection of a fare from each passenger, while crowding of passengers, and the delay incident to boarding the car at congested points of travel are avoided.

Having now set forth the object and nature of my invention and constructions embodying the principles thereof, what I claim 30 as new and useful and of my own invention, and desire to secure by Letters I atent 35 of the United States is,—

1. A car having a body and a platform, a side doorway for the platform, a door therefor, a single wide unobstructed passage between the platform side doorway and 40 the car body for use in common of entering and leaving passengers, and means for moving the door to open or closed position, said means located at the side of said passage opposite and farthest from the doorway and serving to establish a station at 45 which the conductor collects the fares of entering passengers and also controls the operation of the platform side doors.

2. A car having a body and a platform, 50 a side doorway for the platform, a door therefor, a single wide unobstructed passage between the platform side doorway and the car body for the use in common of entering and leaving passengers, said passage 55 extending the full width of the car body space where merging with the platform, and means for operating said door, and controlling devices therefor, said controlling devices located at the side of said passage 60 and serving to establish a station at which the conductor collects the fares of entering passengers and also controls the operation of the platform side doors.

3. A car having a body and a platform, 65 a side doorway for the platform, a door

therefor, a single wide unobstructed passage between the platform side doorway and the car body for the use in common of entering and leaving passengers, said passageway extending the full width of the car body space where merging with the platform, means for operating said door, and controlling devices therefor, said controlling devices being located at the side of said passageway opposite and farthest removed 70 from the platform side doorway and serving to establish a station at which the conductor collects the fares of entering passengers and also controls the operation of the platform side doors.

4. A car having a body and a platform, a side doorway for the platform, an entry way between the platform and car body, an unobstructed single wide passage between said side doorway and said entry way, a door for the side doorway, and means for operating said door, said means being controllable from a point located at one side of said passage, and adjacent said entry way and serving to establish a station at which the collection of fares of entering passengers and also the operations of the platform side doors are controlled.

5. A car having a body and a platform, a side doorway for the platform, an entry way between the platform and the car body, an unobstructed single wide passage between said side doorway and said entry way, a bulkhead partition defining one side of said entry way, a door for the side doorway, and means for operating said door, and controlling devices therefor, said devices located adjacent said bulkhead partition and serving to establish a station at which the collection of fares of entering passengers and 95 also the operation of the platform side doors are controlled.

6. A car having a body and a platform, a side doorway for the platform, doors cooperating to close said doorway, a single wide unobstructed passage between said side doorway and the car body for use in common of entering and leaving passengers, and means for independently opening and closing said doors, said means located at the 110 side of said passage opposite and farthest from the side doorway, and serving to establish a station at which the conductor collects the fares of entering passengers and 115 also controls the operation of the platform side doors.

7. A car having a seating portion and a boarding and alighting portion, a side doorway for the boarding and alighting portion, doors for said doorway, a single wide unobstructed passage between said side doorway and the seating portion of the car for use in common of passengers entering and leaving said seating portion, and means for moving said doors to open or closed posi- 125 130

tion, said means located at the side of said passage opposite and farthest from the doorway and serving to establish a station at which the conductor collects the fares of 5 entering passengers, and also controls the operation of said side doors.

In testimony whereof I have hereunto set

my hand in the presence of the subscribing witnesses, on this 6th day of September A. D. 1910.

HAROLD ROWNTREE.
